UNITED STATES PATENT OFFICE.

LINWOOD M. WHITEHEAD, OF NORFOLK, VIRGINIA.

BARREL-TALLYING MACHINE.

1,406,314.

Specification of Letters Patent. Patented Feb. 14, 1922.

Application filed October 17, 1919. Serial No. 331,333.

To all whom it may concern:

Be it known that I, LINWOOD M. WHITEHEAD, a citizen of the United States, and a resident of Norfolk, Norfolk County, and

5 State of Virginia, have invented certain new and useful Improvements in Barrel-Tallying Machines, of which the following is declared to be a full, clear, and exact description.

10 This invention relates to barrel tallying machines, and its principal object is to provide simple and efficient means for accurately registering or tallying the number of barrels rolled over the same. It is well known, to those skilled in the art, to which this invention pertains, that in loading freight cars, vessels or other carriers, with barrels, or in unloading them, or in moving them into or from warehouses, freight 15 houses, wharfs and the like, a tally or record is kept of the number handled, and this is usually done by an attendant. The same is done when truck loads of merchandise is handled. One of the objects of the present 20 invention is to provide an attachment, which is capable of ready attachment to and removal from a tallying machine for tallying truck loads, a type of which is shown and described in my prior application for patent 25 on tallying machines, filed August 11, 1919, Serial No. 316,840, to which reference is herein made. Another object of the present invention is to provide a barrel tallying machine capable of accurately tallying barrels 30 of large or small diameter. Another object is to provide a barrel tallying attachment which is capable of operation with a platform-lever-operated tallying machine, of practically any type, without necessitating 35 many, if any, alterations or additions to the internal mechanism thereof.

The invention is clearly illustrated in the accompanying drawings, in which:—

Fig. 1 is a perspective view of a barrel 40 tallying machine embodying a simple form of the present invention and illustrating a barrel resting on its platform; Fig. 2 is a vertical cross section taken through the platform; Fig. 3 is a detail, side elevation of a 45 fragment of the platform and an upright support for the barrel actuating arm; Fig. 4 is a fragmental vertical, longitudinal section through the platform and cabinet; Fig. 5 is a rear view of the cabinet, case or com- 50 partment with the back wall removed and

the upper portion broken away, and Fig. 6 is a detail, vertical fragmental section taken on the line 6—6 of Fig. 5.

The platform, compartment, platform levers, register mechanism and register actuating devices may be substantially identical with those of the tallying machine disclosed in the prior application above mentioned and require no detailed description so far as this specification is concerned. 60 Briefly, the truck operated tallying machine illustrated herein comprises, a platform 15 having handles 23 at one end, and rollers 24 at the other end, whereby it may be conveniently moved about. Inclined approaches 65 16, 17 extend sidewise from the platform and have guides 18 secured thereto, to properly direct the course of a truck over the platform levers, shown at 25, 26, 27, and 28, the 70 functions of which are fully set forth in the application referred to. Spaced, crosswise extending boards 20, 21 and an angle iron 19 are secured upon the platform to provide ways for the truck wheels between them, and the board 21 also furnishes a stepping 75 place for the workmen walking over the platform. In the present instance the barrels are rolled over the board 21.

At one end of the platform is an upright compartment 22 in which is contained the 80 secondary levers 25^a 26^a 27^a and 28^a, connected to the platform levers by links 25^b 26^b 27^b and 28^b, and the secondary levers 25^a 28^a are connected by a link 28^d as in my prior application. The secondary lever 25^a 85 is connected to the detent 29 by the link 25^d, bell crank lever 30 and link 31; the secondary lever 26^a is connected to the link actuating arm 33 by the link 26^d and the secondary lever 27^a is connected to the lower link 36 90 by a link 37. The link 36 cooperates with an upper link 35, (when operatively connected) to actuate the register actuating arm 42 when the platform lever 27 is depressed by a truck passing over the platform 95 in the proper direction. The lower link 36 is guided in brackets 38, 39 and the upper link 35 is guided in a rocking bracket 41. A link releasing arm 44, spring actuated in one direction by a spring 45 acts to disconnect the links 35, 36. The arm 42 carries a spring actuated pawl 56 which engages with a ratchet wheel 53 fast on the shaft 54 of the register mechanism. 100

A spring actuated detent 57 engages with 110

the teeth of the ratchet wheel 53 and prevents retrograde movement thereof. A spring 42^a connected to the register actuating arm 42 acts to swing it upward against 5 a stop 42^b and a stop 56^a engages the pawl 56 when the arm 42 reaches the upper limit of its movement and positively arrests further movement of the ratchet wheel 53. The arm 42 is connected to a gong (not shown) 10 by a link 96, which sounds the gong each time the register is actuated. As in the machine of my prior application, the downward movement of the arm 42, (caused by the platform lever 27 being depressed by a truck passing in the proper direction), advances the pawl 56 one tooth on the ratchet wheel 53 and the upward movement of said arm 42 causes the pawl 56 to advance the ratchet wheel one tooth, and therewith the 15 hands 50, 51 of the dials 48, 49. As in the machine of my prior application a barrier 68 may be employed which is automatically moved over the platform when the predetermined number of loads have been moved 20 across the platform. A machine built in accordance with the above brief description, operates to register the number of truck loads passing over the platform levers in the proper direction, and operation of the register is prevented when trucks are moved over the platform in the reverse direction. In tallying barrels with the attachment, forming the 25 subject matter of the present invention, the barrels must be rolled over the platform in the proper direction to cause the machine to register or tally, but the actuation of the register mechanism is accomplished entirely independent of the platform levers.

In the barrel tallying mechanism, as illustrated in the accompanying drawings, the 30 register actuating arm 42 and all parts, which are operated thereby, are actuated by an arm, which normally stands in the path of travel of the barrels as they are rolled over the platform board 21. In its simplest form the barrel tallying device comprises an upright standard or bracket A, which is provided with feet a, that may be detachably secured to the platform 15 by bolts and 35 wing nuts a¹. At the upper end of the standard A, is formed a bearing a² in which is journaled a register actuating rock shaft B, the other end of which is detachably connected with a short rock shaft E journaled 40 in bearings F—G secured respectively to the case or compartment 22 and gear case member 32. Conveniently the short rock shaft E, may be notched at its outer end, and the adjacent end of the rock shaft B may be 45 formed with a flattened portion fitting in the notched end of the shaft E and secured thereto by a bolt and nut e; obviously, any other simple form of coupling may be provided between the rock shafts B, E.

50 Secured upon the rock shaft B, above the

platform board 21, is an arm C, which is forked at its free end and has a roller c, journaled between the forks. The arm is adjustably mounted on the rock shaft C, by a set screw c¹ which is threaded in the arm C and bears against the rock shaft B. The adjustable feature is provided to accommodate the device to barrels of various diameters. 70

Upon the outer end of the rock shaft B 75 is secured a regulating arm H, which is provided with a part h that plays between the standard A and a stop h¹ secured thereto; A set screw h² threaded in the arm H and bearing against the rock-shaft B fixedly 80 secures the arm thereto and permits of its angular adjustment thereon.

The arm H limits the rocking movement of the rock shaft in both directions, which is important to the operation of the register 85 actuating arm 42, with which the rack shaft B is indirectly connected.

The short shaft E is connected to the arm 42 by suitable mechanism, constructed and arranged to transmit the rocking movement 90 of the rock shaft to the arm 42. In the simple means shown for accomplishing this result, an arm I, is secured on the inner end of the rock shaft E, and is connected to one arm of a bell crank lever K by a link J, the other arm of the bell crank lever K being connected to the register actuating arm 42 by a link L. The bell crank lever K is pivotally mounted on the gear case member 32. Movement of the arm I, in the 100 direction of the arrow thereon in Fig. 5 moves the link J, bell crank link K, link L, and arm 42 in the directions of the arrows applied thereto, thereby advancing the pawl 56 one tooth. Movement of the same parts 105 in the opposite direction returns the pawl 56 to former position and advances the ratchet wheel 53 and register one step.

In the operation of the tallying machine, when the barrel tallying attachment is used, 110 the barrels (one of which is seen at M in Fig. 1) are rolled across the platform in the direction of the arrow x (Figs. 2, and 5.) The arm C is normally held in the position seen in full lines in Fig. 2 by 115 the regulating arm H which at that time rests against the standard A. As the barrel is rolled over the platform board 21 it contacts with the roller c, and swings the arm C upward, thereby turning the rock 120 shafts B, E, and swinging down the arm 42 through the instrumentality of the arm I, link J, bell crank lever K and link L. When the barrel passes the roller c, the arm C drops back to the position seen in 125 full lines in Fig. 2 where it is held by the arm H which strikes the standard at the lower limit of movement of said arm. For convenience I have illustrated a barrel M¹, at a position just prior to its engagement 130

with the roller *c*, and also at *M*² where the roller *c* and arm *C* have been swung to the upper limit of movement.

For adjusting the arm *C* to accommodate barrels of other diameters, the set screw *c*¹ is loosened, a barrel, of a given diameter, rolled under the roller *c* and the latter raised until it rests on the barrel at a point directly over its axis, the arm *H* at 10 the same time being held against the stop *h*¹, after which the bolt *c*¹ is screwed down tightly against the rock shaft. Barrels of the same diameter may now be rolled across the platform board 21 in the proper direction 15 and tally will be kept by the register mechanism of the number passing over the platform.

In my prior Patent No. 1234242, dated July 24, 1917, improvements in freight tally, is illustrated an alarm and a barrier. The alarm is sounded shortly before the last load is moved over the platform and the barrier is released and swung over the platform immediately after the last of the 25 predetermined number of barrels have been rolled over the platform. The alarm and barrier may likewise be used in the present device.

To tally truck loads, the rock shaft *B* 30 is disconnected from the short rock shaft *E*, the wing nuts *a*¹ unscrewed, and the standard, with its rock shaft *B* and arm *C*, is removed, thereby permitting the truck wheels to pass over the platform levers and 35 actuate the tallying and associated mechanism as set forth in the prior application.

It is to be observed that when the barrel tallying attachment is used, the link 35 is reciprocated idly by the arm 42 and that 40 when the barrel tallying attachment is disconnected, the link *L*, bell crank lever *K*, link *J*, arm *I* and short rock shaft *E* are actuated idly.

To prevent accidental operation of the 45 tallying mechanism by the depression of the platform levers, (when the barrel tallying attachment is used,) I provide a release lever *O*, pivotally supported on the compartment 22 and having an end *P* arranged 50 to engage and depress the platform lever 25, when the lever *O* is swung down, as seen in Fig. 4. A spring catch *R* is secured to the compartment 22 in position to engage the handle portion of 55 the lever *O*, when swung up, and thereby releasably hold said lever in raised or inactive position. In such position, the platform levers are free to operate the tallying mechanism. When swung down, however, 60 the end *P* of the lever *O* holds the platform lever 25 down, thereby preventing the detent 29 from holding the link locking arm 33 in the position occupied when coupling the link 35, 36.

65 By the term "attachment" is meant the

standard *A* rock shaft *B* and parts directly and fixedly connected thereto. The connections between the rock-shaft *B* and arm 42 may or may not be a permanent part of the machine with which they are used, and may be readily coupled thereto to convert the machine into a barrel tallying device. 70

More or less variation of the exact details of construction is possible without departing from the spirit of this invention; I desire, therefore, not to limit myself to the exact form of the construction shown and described, but intend, in the following claims, to point out all of the invention disclosed herein. 75

I claim as new and desire to secure by Letters Patent:

1. An attachment for converting a truck load tallying machine of the type containing a platform, platform levers and tallying mechanism actuated thereby, into a barrel tallying machine, comprising a rock shaft adapted to extend lengthwise over the platform of the tallying machine, a support for one end of said rock shaft detachably secured to the platform, an arm secured to said rock shaft and having an end arranged in the path of movement of objects which are rolled over the platform and under the arm, and operative connections between one end of said rock shaft and tallying mechanism of the tallying machines for actuating said tallying mechanism. 80

2. An attachment for converting a truck load tallying machine of the type containing a platform, platform levers and tallying mechanism actuated thereby, into a barrel tallying machine, comprising a rock shaft adapted to extend lengthwise over the platform of the tallying machine, operative connections between one end of said rock shaft and tallying mechanism for actuating said tallying mechanism, a support for the other end of said rock shaft detachably secured to the platform, an arm secured to said rock shaft intermediate its ends and having one end arranged in the path of movement of objects which are rolled over the platform and under the arm, said arm being adjustably mounted on said rock shaft to accommodate barrels of different diameters, and means on said rock shaft having a limited amount of angular movement, for fixing the rocking movement of said rock shaft, irrespective of the position of the arm thereon. 100

3. A truck load tallying machine, capable of being converted into a barrel tallying machine, and having a plurality of platform levers which are successively depressed by truck wheels passing over them, setting mechanism and register actuating mechanism connected to and operated by certain of said platform levers, and holding means for said setting mechanism operatively connected to one platform lever, and means for 110

125

holding said last mentioned platform lever in depressed position to render said holding means ineffective, whereby the platform lever which actuates the register actuating mechanism is rendered ineffective to actuate the register actuating mechanism when the device is used as a barrel tallying machine.

4. In a tallying machine, tallying mechanism, lever operated actuating mechanism including connectable and disconnectable links, platform-lever-operated setting mech-

anism for connecting said links, means for holding said setting mechanism in set position, platform-lever-operated means for moving said holding means into inactive position, and a member for positively holding the lever of the last mentioned means in depressed position, whereby the other lever operated means are rendered ineffective, substantially as and for the purpose set forth. 15 20

L. M. WHITEHEAD.
